UNITED STATES PATENT OFFICE.

JOHN B. ANDERSON, OF MANHATTAN, KANSAS.

HARNESS-SUPPORT.

SPECIFICATION forming part of Letters Patent No. 668,432, dated February 19, 1901.

Application filed June 21, 1900. Serial No. 21,045. (No model.)

To all whom it may concern:

Be it known that I, JOHN B. ANDERSON, a citizen of the United States, residing at Manhattan, in the county of Riley and State of Kansas, have invented certain new and useful Improvements in Harness-Supports; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in harness-supports especially adapted for supporting in a horizontal position harness provided with collar and hames, but which is also adapted for use for various other purposes.

20 My invention consists in a plate to be secured to the wall or other suitable support and may be provided near its upper end with a spur-hook, a flange or rib extending vertically along the outer surface of said plate,

25 two supporting-ears through which a pivotal pin is passed, a slot extending between the ears, combined with an arm having a projection at its inner end to be inserted in said slot, and flanges upon opposite sides of said

30 arm to overlap the top edges of the ears, so that when the arm is in a horizontal position all weight is taken from the pivotal pin, which may be dispensed with, if preferred. Said arm may also be provided with a spur-hook

35 near its outer end for the purpose of aiding in keeping the harness extended upon the arm.

In the accompanying drawings, Figure 1 represents a side elevation of a harness-support embodying my invention, one of the ears 40 being broken away, so as to show the slot in the inner end of the arm, which is shown in a suspended position in dotted lines. Fig. 2 is a front elevation of the base or plate alone.

Similar letters of reference indicate like 45 parts.

A represents a plate of any suitable shape or size and is secured to the wall by means of screws or other suitable fastenings. From the outer side of this plate near its upper end 50 projects the spur-hook B, upon which it is designed to place a portion of the harness before raising the arm. Extending vertically

along the middle of the plate from this spur-hook to the top of the ears D it is considered advisable for the purpose of strength to provide a rib or flange C. The two ears D project outwardly from the plate any distance desired and are separated sufficiently to allow the lower edge of the arm F to be inserted freely between them. Through the plate near 55 its lower end is formed the slot G, which is located between the vertical sides of the two ears D. This slot, as shown in Fig. 2 and by dotted lines in Fig. 1, is made through the plate at the lower end of the rib or flange C 60 between the two ears D, and in which slot the short projection H upon the inner end of the arm F is inserted. Through the outer end of the two ears D is passed a pivotal pin I, which, however, is brought into play only 65 when the arm F is dropped into the vertical position shown in dotted lines, so as to be out of the way when not in use.

The arm F is provided with a horizontal flange J on opposite sides of the top edge not 75 only for the purpose of strengthening the arm, but for the purpose of forming two supports at the inner end of the arm, where they overlap the top of the two ears D. At the inner end of the arm is formed the longitudinal slot 80 L, through which the pivotal pin I passes, and upon the outer end of the arm is formed a spur or projection O, which extends upwardly toward the plate, as shown. Beyond the spur O the top surface of the arm is curved downward and outward, terminating in a horizontal support or hook P upon the outer end of the arm F, principally for the purpose of holding the harness extended upon the arm.

When the arm F is to be dropped into the 90 vertical position shown by dotted lines, it is only necessary to draw the arm horizontally outward until the projection H is cleared from the slot and the lower end of the rib or flange C, when the arm will swing downward to a 95 vertical position and be supported by the pivotal pin I. This is the only time when this pivotal pin is to be brought into use. Hence a very light pin may be used. When the arm is to be brought into use, its outer end is raised 100 until the two flanges J strike against the top edges of the ears D, when the arm is pushed inwardly the distance of the length of the slot L, when the projection H again enters slot

G and the top flat edge of the arm engages with the lower end of the rib or flange C. As before stated, the inner ends of the two flanges J and the projection H then support the arm 5 F in a horizontal position, with the weight of everything hung thereon.

What I consider the most convenient method of suspending a harness having hames is to catch the bottom hames-strap over the spur-10 hook B, raise the arm to a horizontal position, allowing it to engage the top hames-strap as it ascends, and then by simply pressing the arm back till it is inserted in slot G, as described, the operation is completed. To take 15 the harness from the support this process is reversed.

The present method of suspending the harness from a peg or hook secured to the wall, with the outer or top hames-strap supported 20 by a swinging rod attached to the ceiling, is unhandy in its operation, and the rod itself is in the way of hanging other articles on the walls above the harness. Furthermore, with 25 my support the harness may, if desired, be hung close to the ceiling, which is not practicable with the present method referred to above.

Having thus described my invention, what I claim as new, and desire to secure by Letters Patent, is—

1. In a harness-support, the wall-plate provided with a slot, supporting-ears upon opposite sides of said slot, combined with an arm having a projection upon its inner end which extends into the slot in the plate and 35 which arm is also provided with horizontal flanges on opposite sides thereof and which overlap the top edges of the ears, so that the arm is supported in a horizontal position wholly by the projection upon its end and the 40 two flanges upon its upper edge, substantially as set forth.

2. In a harness-support, a wall-plate and a spur-hook projecting from the upper end of 45 said plate, combined with a pivoted vertically -swinging and longitudinally -movable arm extending from said plate, substantially as and for the purposes set forth.

In testimony whereof I affix my signature in presence of two witnesses.

JOHN B. ANDERSON.
